UNITED STATES PATENT OFFICE.

MAX J. MARYMONT, OF BROOKLYN, NEW YORK.

WOMAN'S HAND BAG OR POCKETBOOK.

Application filed November 28, 1927. Serial No. 236,075.

This invention relates to women's pocket books or hand bags and has for its principal object to provide a hand bag or similar article in which a secret pocket is contained 5 adapted to be entirely concealed from view and which can not be easily discovered.

With pocket books of this character as hitherto constructed, the location of the secret pocket is such that the presence thereof 10 is easily betrayed.

This drawback is obviated with this invention.

With this and other objects in view my 15 invention substantially consists in the novel construction, arrangement and combination of parts, as will be hereinafter more fully described and defined in the appended claims.

My invention will be more fully understood by reference to the accompanying drawing which constitutes part of this specification and in which similar reference characters denote corresponding parts, Fig. 1 being a perspective view of the improved 25 pocket book showing the secret pocket concealed; Fig. 2 a similar view to Fig. 1 of a part of the pocket book showing the secret pocket opened and Fig. 3 is a cross section on line 3—3 of Fig. 1.

In the drawing 10 and 11 denote respectively the front and back portion of the pocket book, in which as usual, a plurality of pockets are provided, the construction of which, however, need not be described, as 35 they do not form part of this invention. 12 denotes the flap formed by the extension of the back portion 11 of the pocket book and adapted to fold over the front portion 10 to close the pocket book.

Attached at its side edges and bottom edge as at 13', 13'', to and covering the entire inner face of said back portion 11 is a flexible member 13. The upper end of said member is extended as at 13'', to also cover 40 a part of the inner face of the flap 12 and is attached thereto at its side edges, as at 13'', so that said member 13 forms with said back portion 11 and with the lower part of the flap 12 a pocket 14 (Fig. 3) adapted to be 45 concealed from view when the pocket book is opened. To this end I provide a second flexible member 15 which is suitably attached at its bottom and side edges to and extends over the front face of that part of 50 the member 12 which covers only the back part 11, but not the flap 12. This second

member 15 together with the mentioned portion of the member 13 will thus form a second pocket 16 which is adapted to be visible when the pocket book is opened. The inner 60 lining 17 of the flap 12, of suitable material, usually of leather, is stitched to the flap 12 along its upper edge, as at 17' and along its side edges, as at 17''. The side stitches 17'' do not extend all the way down but 65 terminate slightly short off the upper end of the member 13, as at 17''. The lower unattached portion of the lining 17 is extended as at 17''' beyond the lower end of the flap 12, and is slightly reduced in width, as at 70 17''', so that it may freely and easily pass into the visible pocket 16, as shown in Fig. 3, in order to conceal the presence of pocket 14. When extending into this visible pocket 16 it bears against the outer face of the member 13, so that said extended part 17''' appears to be the lining or rear wall of said 75 pocket and does not betray the presence of the pocket 14.

To open or uncover the secret pocket 14 80 the extended part or flap 17''' is pulled out from the pocket 16 and folded or rolled upwardly, as shown in Fig. 2.

I do not wish to restrict myself to the details of the construction shown and described, since various modifications may be made without departing from the principle 85 of my invention.

What I claim is:

1. A woman's pocket book or the like, 90 comprising a body having a front and back portion, the back portion being extended to form a flap adapted to fold over the front portion, two adjacent pockets between said front and back portions, one of said pockets 95 serving as a secret pocket and having its back wall formed by the back of said body and a part of said flap and a lining for said flap having an unattached extended portion at its lower end adapted to be passed into said other pocket so as to conceal the presence of said secret pocket.

2. A woman's pocket book or the like, 100 comprising a body having a front and back portion, said back portion being extended to form a flap adapted to fold over said front portion, a flexible member stitched along its side edge and bottom to and extending over the entire inner face of said back portion 105 and over the inner face of a part of said flap 110 to form a secret pocket, a lining converging the inner face of said flap and attached

thereto at its side edges and upper end edge, the lower end of said flap being unattached and extended below the upper edge of said flexible member and a second flexible member in said body which extends over the part of the front wall of said secret pocket confined within the body and forming with said

part a second pocket, the extended part of said lining being adapted to be passed into said second pocket and to thereby conceal ¹⁰ the presence of the secret pocket.

In testimony whereof I affix my signature.

MAX J. MARYMONT.
